(57) **CLAIM**

The ornamental design for a vehicle floor mat, as shown and described.

DESCRIPTION

FIG. 1 is a front perspective view of a vehicle floor mat showing our new design in accordance to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of a vehicle floor mat showing our new design in accordance to a second embodiment;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines in the figures illustrate portions of the vehicle floor mat that form no part of the claimed design. The dash-dot lines indicate a boundary or perimeter of the vehicle floor mat and form no part of the claimed design.

1 Claim, 8 Drawing Sheets
